(57) **CLAIM**

The ornamental design for a weight bench, as shown and described.

DESCRIPTION

FIG. 1 is a front perspective view of a weight bench, showing my new design;

FIG. 2 is a rear, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of the area 9 in FIG. 1;

FIG. 10 is an enlarged view of the area 10 in FIG. 1;

FIG. 11 is an enlarged view of the area 11 in FIG. 2;

FIG. 12 is an enlarged view of the area 12 in FIG. 2;

FIG. 13 is an enlarged view of the area 13 in FIG. 3;

FIG. 14 is an enlarged view of the area 14 in FIG. 3;

FIG. 15 is an enlarged view of the area 15 in FIG. 5; and,

FIG. 16 is an enlarged view of the area 16 in FIG. 7.

The dashed broken lines in the figures are for the purposes of illustrating portions of the weight bench, which form no part of the claimed design.

The dash-dot-dash broken lines are for notating enlarged views, which form no part of the claimed design.

1 Claim, 11 Drawing Sheets
